UNITED STATES PATENT OFFICE

JOHANN GABLER, OF ETTLINGEN, GERMANY

WEFT HOLDING DEVICE

Application filed November 10, 1927, Serial No. 232,397, and in Germany November 16, 1926.

This invention relates to a device in gripper weaving looms for holding the weft end cut off inside the edge, the warp shed being open, up to the moment of beating up the weft, in order to obtain a firm edge to the fabric. As known from experience, the short cut off weft end has the tendency to slip out of the shed, mainly when it has been cut off close to the selvedge, this being on the other hand advisable in order to obtain selvedges which are not too wide. This object is perfectly attained, according to the present invention by holding the weft end in the shed by pressing together the warp threads until the beating up of the weft.

The invention is more particularly described and shown, by way of example, in the accompanying drawings, wherein

Fig. 1 is a side elevation,

Fig. 2 a top plan view and

Fig. 3 a part elevation in enlarged scale.

When the loom is working, the weft 1 is inserted double up to the middle of the shed and cut through as close to the edge 2 as possible and at the moment when the slay 3 is in the extreme backward position.

Previous to the cutting action and previous to the slay reaching its extreme backward position (position shown in full lines in Fig. 1), a slotted or fork-shaped slide 4 is pulled forward over the weft 1 by means of a flexible strap 5, for instance of leather or the like, which latter is fixed with its one end to the slay carrier by means of a screw 7 and with its other end on the regulating screw 6. On the regulating screw 6, which is screwed with its externally threaded end into the internally threaded rear portion of a guide piece 11, are slidably mounted on its remaining smooth cylindrical part, as a whole, the rear portion 4a of the slide 4, an intermediate disk 4b of suitable material 4b, the one end of the leather strap 5 and a centrally bored fixation screw 6a, which latter carries the end of the leather strap and the intermediate disk to be

screwed with its externally threaded end into the internally threaded rear portion 4a of the slide 4.

The operation is as follows:—

Suppose the slay 3 travelling backwards, e. g. away from the slide (position shown in full lines in Fig. 1), the strap 5 will pull the slotted slide 4 over weft 1 as the one end of said strap is fixed to the slay-carrier and the other end thereof to the displaceable slide 4. Simultaneously said slotted slide 4 grips, with its slotted portion, over the warp ends 8 and 9 (Fig. 3) whereby the weft 1 is securely held in its position. The backward movement of the slide 4 is limited by the rear portion of the slide butting against the supporting- and guide piece 11, whilst its forward movement is limited by the head of the regulating screw 6 and forward travel of the slay-carrier 3.

When the slay carrier 3 returns to the position shown in Fig. 2 in dotted lines, the reed 10 will push back the slide 4 and thus release the weft thread 1 and the warp threads 8 and 9. This action will take place as long as the loom is working.

I claim:—

1. In combination with gripper weaving looms, a weft holding device comprising a slay carrier, a slay, a reed, a guide piece suitably mounted on a support, a regulating screw with an externally threaded end portion screwed into the internally threaded rear portion of said guide piece the remaining portion of said screw being smooth, a slotted slide free-movably mounted in said guide piece, the rear portion of said slide provided with an internal thread being mounted on the regulating screw, an intermediate disk mounted on said regulating screw, a flexible strap suitably fixed with its one end to the slay carrier and with its other end on the regulating screw, a centrally bored fixation screw slidably mounted on said regulating screw and carrying the one end of said strap and the intermediate disk, an externally

threaded small end portion of said fixation screw screwed into the internal thread of the rear portion of the slide so as to slide, to and fro as a whole, on the smooth portion of the regulating screw, which latter may regulate the degree of movement of said slide by being tightened or untightened.

2. In combination with gripper weaving looms, a weft holding device as described in claim 1, whereby the slotted slide grips at its backwards motion, due to a pull of the strap imparted to said slide, simultaneously over the front weft thread and over the first two warp threads thus holding the front weft thread clamped between the first two warp threads previous to the cutting action.

In testimony whereof I affix my signature.
JOHANN GABLER.
